Inventor

William Wilbarger,
By Frederick V. Winters,
Attorney

UNITED STATES PATENT OFFICE.

WILLIAM WILBURGER, OF BROOKLYN, NEW YORK.

BINDING POST FOR LOOSE-LEAF BOOKS.

Application filed November 14, 1921. Serial No. 515,012.

To all whom it may concern:

Be it known that I, WILLIAM WILBURGER, a citizen of the United States, and resident of Brooklyn, in the county of Kings and State of New York, have invented certain new and useful Improvements in Binding Posts for Loose-Leaf Books, of which the following is a full, clear, and exact specification.

This invention relates to binding posts for loose leaf books and has for its object to provide a resilient binding post for use with rigid book covers so that said post may expand and contract as the covers of the book are spread apart or folded together in opening and closing said book.

A further object is to provide a sectional binding post of this kind, both sections of which are resilient and one section detachably connected to the other. Another object is to provide the resilient sections of the binding post with suitable heads fastened thereto in such a manner that they will not be displaced when said sections are expanded or bowed. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a section of a book having rigid covers connected by a resilient binding post constructed substantially in accordance with this invention, the book being closed.

Figure 2 is a similar view of the book open, and

Figure 3 is a detailed section of the binding post drawn to a larger scale and showing the means of fastening the heads on the section of said post, as well as the detachable screw connection between said sections.

The book illustrated in Figures 1 and 2 has stiff covers 1 and 2 connected by flexible hinge portions 4 and 5 to a stiff back member 3. The leaves 16 are detachably held between the covers by binding posts constructed of coiled resilient wire as best shown in Figure 3. Any suitable number of these binding posts may be employed. The leaves are provided with perforations or passages

17 through which the binding posts extend. Each binding post is made in two sections, a larger section 6 of resilient coiled wire and a smaller section 10 of similar construction. The larger section 6 has a head preferably made in two parts. The inner part of said head has a tubular portion or sleeve 7 fitting around a plurality of coils of the wire forming said larger section of 65 the shank of the post, and an outwardly turned annular flange 18, while the outer part 8 is preferably made dome-shaped and has an inwardly turned peripheral flange 19 engaging the flange 18 of the inner part. 70 The inner end of the sleeve 7 is bent inwardly or crimped at 14 between adjacent coils of the section 6, whereby the head is rigidly connected to said section. A head similarly formed with a sleeve 11 and dome-shaped member 12 is connected to the inner section 10 of the shank of the post in the same manner as just described in connection with the head on the outer section 6 of said shank. Said outer section 6 is preferably made longer than the inner section 10 so as to extend substantially through the book, as illustrated in Figure 1.

In assembling the book the outer sections 6 of the binding posts are inserted from one side, the sleeves 7 engaging perforations 9 in the cover 2 and the portions 8 of the heads engaging the outer surface of said cover, in which position the shanks 6 extend substantially through the book, that is, from the 90 cover 2 to the cover 1. After the leaves 16 are placed in position with their perforations 17 engaging around the shanks 6 of the binding posts, the inner sections 10 of said posts are inserted through perforations 13 in the cover 1 and screwed into the free ends of the sections 6, see Figs. 1 and 3. The inner sections 10 of the shanks of the binding posts are made long enough to extend for some distance into the outer sections, as indicated at 15 in Figs. 2 and 3, so that said sections will hold together under the strain of expansion when the book is opened. As shown in Fig. 2, the opening of the book stretches or expands the resilient coils of which the shanks of the binding posts are made without separating the engaging portions 15 of the sections of said shanks. When the book is opened the binding posts are bowed or arched, as well as expanded, so that the leaves 16 may lie substantially flat and be conveniently turned.

2
As soon as the book is closed and the strain is removed from the shanks of the binding posts they contract to their original form, as shown in Figs. 1 and 3.

5 I claim:

1. A binding post for loose leaf books having its shank composed of two sections of coiled resilient wire, one section having screw connection with the other.
- 10 2. A binding post for loose leaf books having its shank formed of coiled wire, and a head fitted over the end of said shank and secured in place by having portions thereof bent inward between adjacent coils of the
15 wire.

3. A binding post for loose leaf books having its shank composed of two sections of coiled resilient wire, one section having screw connection with the other, and the outer section extending substantially through 20 the book.

4. A binding post for loose leaf books having its shank composed of two sections of coiled resilient wire, one section having screw connection with the other, and both 25 sections having heads secured to their outer ends.

In testimony whereof I have signed my name to this specification.

WILLIAM WILBURGER.
